UNITED STATES PATENT OFFICE.

LESLIE R. TRIPP, OF TOPEKA, KANSAS, ASSIGNOR OF ONE-THIRD TO JOSEPH H. CLOSE
AND ONE-THIRD TO ULYSSES G. CHARLES, BOTH OF TOPEKA, KANSAS.

MARBLE-SHOOTING MECHANISM.

Application filed April 30, 1926. Serial No. 105,844.

My invention relates to a marble shooting mechanism having a pistol shape for the structure in general.

The object of my invention is to provide a mechanism in which to place a marble and means for discharging it therefrom with a degree of accuracy as to marksmanship.

A further object of my invention is to construct a mechanism having the appearance of an automatic pistol of such size that can be carried in the pocket.

A still further object of my invention is to provide a marble shooting mechanism having variable means for the power of the plunger in discharging the marble.

A still further object of my invention is to provide a marble shooting mechanism that will accommodate marbles of different diameters, and having means to retain the marble within the race when vertically or otherwise positioned.

These and other objects will hereinafter be more fully explained.

Referring to the drawings:

Fig. 1 is a side elevation of the mechanism, parts removed for convenience of illustration.

Fig. 2 is a top view of Fig. 1.

Fig. 3 is an end view looking in at the muzzle.

Fig. 4 is a sectional view taken on line A in Fig. 1.

Fig. 5 is a fragmentary detail view of the retainer spring.

Referring to the drawings in detail, 1 is the barrel, 2 is the grip. In the outer end of the barrel is a groove 3; said groove being semi-elliptical in shape, the major axis being vertical. The object of this form of groove is that marbles of different diameters will engage on the side walls thereof; and a marble of minimum size as shown at 4 will position in the bottom of the groove as shown in Fig. 3. As a means to retain the marble, I have provided a leaf spring member 5; said spring being integral with the extended portion reaching rearward near the breech of the barrel as at B. The end contacting the marble is provided with a depression as at C conforming to a minimum sized marble but the depression will be sufficient to engage with marbles of different diameters retaining them substantially in position.

Rearwardly positioned to the marble is a

solid portion of the barrel as at 6. Centrally positioned therethrough is an aperture 7 adapted to receive a plunger 8; the said plunger having a head 9 integral therewith as a stopping means when contacting with the solid portion as at D. Diametrically positioned across the head is a channel 10 in which is seated an elastic band 11, the opposite end of the band engaging in a notch 12 at the muzzle of the pistol. On the lower side of the head is a detent 13 adapted to engage in notches 14 hereinafter described. The head 9 is adapted to slide in an opening 15. The rear portion of the spring member 5 is a support for a guide 16; said member having a curvature in the side thereof as at E conforming to the diameter of the head 9. And as a convenient means to remove the plunger or to replace an elastic band, the screws 17 are removed and by springing the member upward a band may be placed within the opening 15 and likewise the plunger removed by sliding it rearward until the end thereof disengages from the aperture.

Positioned in the grip within a slot F is pivotally mounted a trigger 18 having notches 14 longitudinally positioned thereon. The object of the plurality of notches are, that different tension may be had on the band varying the force of the plunger, when discharging the marble. That is to say, if it is desired to shoot the marble with greater force the plunger will be drawn rearward engaging with the notches farther back on the parallel portion of the trigger with the plunger. When the trigger is drawn downward the notch will disengage from the detent at which time free passage will be had for the detent as it plunges forward to the point D. The trigger is tensioned by means of a spring 19, which is held firmly to the grip between the guard 20 and the grip by means of a screw 21. The opposite end of the guard is attached to the barrel by means of a screw 22. As a means for training the pistol for a shot desired, I have provided a muzzle sight 23 and a breech sight 24. The muzzle sight is positioned on a band 25 functioning also as a supporting means for the side walls of the channel and rigidly attached thereto by pins 26, one being on each side of the muzzle.

The mechanism herein disclosed is designed for playing games with marbles

wherein strong and accurate shots are required. However the marble may be discharged moderately in its force.

To operate the pistol I take hold of the head 9 drawing it rearward to the desired notch in the trigger and place a marble under the spring 7 so that the depression in the end of the spring will engage on the top thereof. Then by sighting the pistol 10 for the desired shot I pull the trigger, at which time the plunger is driven forward contacting the marble with its full force discharging it from under the spring and longitudinally out of the groove. As heretofore stated marbles of different size may be employed and the plunger being of sufficient diameter so that the end thereof will contact the marble driving it axially with the barrel.

20 Such modifications may be employed as lie within the scope of the appended claims.

Having thus described my invention, what I claim as new and desire to secure by Letters Patent is:—

25 1. In a marble shooting mechanism, a grip and a barrel having the shape of a pistol, a groove longitudinally positioned in the barrel, a plunger in axial relation with the groove, guiding means for the plunger, a detent on the plunger; a trigger pivotally connected in axial alignment with the plunger so that the notches on the aligned portion 30 of the trigger with the barrel will angle downward from the pivot point when pulled 35 preventing the detent from contacting with the forward notches from its notch of engagement, an elastic band attached near the muzzle of the barrel, the opposite end of the band engages with the plunger as actuating 40 means therefor, a spring attached to the barrel functioning as a retainer for a marble placed within the groove.

2. In a marble shooting mechanism, a semi-elliptical groove in a portion of the length 45 of the barrel, an aperture through a solid portion of the barrel adjacent the inner end of the groove, an opening in the barrel rearward the solid portion as a reciprocating means for the plunger head, the plunger 50 slidably engaging in the aperture, a spring attached to the top of the barrel to function as a retaining means for a marble positioned

in the groove, a guide member attached to the rear portion of the spring as guiding means for the plunger head, a detent on the 55 head and a trigger having a plurality of notches to engage with said detent, a channel diametrically positioned on the rear plane of the head, an elastic band positioned in the channel, a notch near the end of the barrel to receive the opposite end of the band, a band having a sight laterally positioned thereon, said band functioning as a brace for the side walls of the channel and positioned in close proximity to the muzzle 60 end of the barrel, a sight near the rear end of the spring member at the breech of the pistol, all substantially as shown.

3. In a marble shooting mechanism, a pistol shaped member having a groove in a portion of the barrel to receive marbles of different diameters, a spring having a depression in the end thereof to engage on the marble as retaining means, a plunger in axial relation with the groove, an elastic band actuating a stroke of the plunger to discharge the marble, a trigger having a portion parallel with the plunger, a plurality of notches along the parallel portion to engage with the plunger for a desired 70 force of the plunger, a laterally extending portion from the parallel portion of the trigger as disengaging means for the trigger.

4. In a marble shooting mechanism, a pistol of the kind described having a groove 75 as a guiding means for a marble discharged therefrom, a spring to hold the marble in the rear end of the groove and in axial relation with an aperture, a plunger engaging in the aperture, a head on the plunger as stopping means for the stroke and having a detent as engaging means for a trigger, a trigger having a portion of the ends thereof laterally extending in opposite directions, the rear portion being the pivot point, the 80 front portion to be engaged by the operator as tripping means, notches along the edge of the portion between the laterally extending members as means for varying the tension of the elastic band on the plunger, a 85 spring tensioning the trigger and a guard protecting the trigger and simultaneously attaching the spring to the grip of the pistol.
